Primary Examiner — Holly H Baynham(74) *Attorney, Agent, or Firm* — Banner & Witcoff, Ltd.(57) **CLAIM**

The ornamental design for a bag, as shown and described.

DESCRIPTION

FIG. 1 is a top, front, right perspective view of a bag showing our new design;

FIG. 2 is a right side view thereof; and,

FIG. 3 is a left side view thereof.

The broken lines within the shaded areas represent stitching. The broken lines immediately adjacent to the shaded area represent unclaimed boundaries of the design.

1 Claim, 2 Drawing Sheets# US D851,404 S
